UNITED STATES PATENT OFFICE.

BESSIE KINGSLEY, OF SOUTH VANCOUVER, CANADA.

CHURN.

SPECIFICATION forming part of Letters Patent No. 645,476, dated March 13, 1900.

Application filed June 17, 1899. Serial No. 720,966. (No model.)

To all whom it may concern:

Be it known that I, BESSIE KINGSLEY, wife of William Kingsley, a citizen of the Dominion of Canada, residing at South Vancouver, in the Province of British Columbia, Canada, have invented certain new and useful Improvements in Churns, of which the following is a specification.

My invention relates to improvements in that class of churning having their construction of barrel form, with the trunnions oppositely disposed therefrom, which rest in bearings in a suitable frame, whereby the churn when rotated will be turned endwise to the axis of the barrel.

The objects of my invention are, first, to construct the body of the churn of such a form that its center part, which is in line with the axis of its movement, offers no space or area in which the cream therein will gather and not be properly agitated, as is the case with the churn having a uniform contour of circumference and diameter at this point, and to construct such a body of a material that cannot impart any unwholesome taste or effect to the cream, and consequently to the butter; second, to provide a cover for the churn that is of a cheap and simple construction and that may be secured in a simple and effective manner, and, third, to arrange the bearings for the churn in an adjustable manner, so that the crank-handle may be brought the desired height for the operator, and also to provide a means for holding the churn in an upright or an inverted position while the contents are poured therein or emptied therefrom, respectively. I attain these objects by the mechanism illustrated in the accompanying drawings, in which—

Figure 1 shows an elevation of my churn with the vessel for holding the cream sectioned lengthwise thereof. Fig. 2 is a plan of the churn. Fig. 3 is a detail of the device employed for locking the churn in any position desired, and Fig. 4 is a sectional detail of the vent-plug.

Similar numerals refer to different parts throughout all the views.

The churn 10 is preferably constructed of enameled iron or granite ware. The opposite sides of this are fluted, which flutes are formed

by concave channels 10^a, passing through the swell of the barrel-shaped body. Securely fixed on opposite sides of the churn 10, at the center of straight flutes 10^a, are trunnions 11, 55 which rest on bearings 12, adjustably fixed in the forks 13 of the frame. This frame consists of uprights 14, the cross-bar 15, and the parallel horizontal supports 16, which parts are all securely bolted together and stiffened 60 by the braces 17 and 18, as shown.

The trunnions 11 at their point of bearing are provided with V-shaped cones 11^a, which rest in the grooves in the bearings 12, designed to receive the same. This prevents 65 the churn from having lateral movement on its bearings, which is a very important improvement over the old method.

The bearings 12 are blocks made to fit between the forks 13 and susceptible of being 70 slipped up and down, and they are secured at the desired horizontal plane by bolts 19, having butterfly-heads thereon for turning the hand, threading through straps 20, which inclose the blocks 12 and the forks 13. (See 75 Fig. 3.)

The churn is turned as in the usual way by a crank-handle 21, secured to the end of the trunnions 11. The churn may be locked in a horizontal, upright, or inverted position by 80 a vertical slidable spring-holder 22, fixed to the upright 14 on the opposite side. This spring-holder 22 is secured to the upright 14 in its vertical movable position by straps 23 and when not in use is slipped below the trunnion 11; but when in use the square end of the said trunnion is passed through the opening 22^a therein, which prevents the churn from being turned. Sufficient vertical movement is provided for the holder 22 to allow 90 for the vertical adjustment of the churn, so that it may be locked at any point.

The open end of the churn 10, like the closed end, is of uniform diameter. The cover 24 is provided with an annular groove 24^a to receive the rim of the body 10, and to make the joint tight a strip of cork or other like material is inserted and arranged to expose an even plane in the said groove. At the center of the cover 24 is a rigidly-fixed stud or bolt 95 25, on which is a screw-wheel 26, susceptible of being turned up or down as a nut, and

lying between the said wheel and the cover is a cross-bar 27, which is made to turn on the said bolt.

Pivoted to hinges 28, which are fixed to the opposite fluted sides of the body 10 adjacent to the rim or open end thereof, are levers 29. These levers 29 are looped or widened out and are provided with depending heels or fulcrums 29^a to engage the cover at intervals, and thus keep it pressed down upon the rim of the body 10. The inner ends of said levers are provided with depressions 29^b, in which the ends of the bar 27 are received and held when the screw-wheel 26 is turned down tight.

15 The foregoing arrangement provides a very effective fastening and one that is cheap of construction.

30 indicates a light or sight pane inserted in one side of the cover. This enables the operator to see the various conditions of the cream in the operation of churning the butter without the necessity of removing the cover, and at the opposite end of the churn 10 and fixed in its side is a nipple 31. This 25 is provided with a cap 32, threaded thereon, in the hollow of which is a piece of cork 33, so that when it is screwed up tight the opening will be effectively stopped. For an air-vent a small aperture 32^a is provided in the 30 wall of the cap. This, when the cap is turned back so that the cork 33 is lifted off its seat on the nipple, allows a suitable air-vent.

By reason of the flutes 10^a on the opposite sides of the barrel-framed vessel the cream 35 will be prevented from gathering in cones on opposite sides in line with the axis of its movement, and consequently all parts of the matters in the churn will be uniformly agitated, whereas in the old style, as the churn 40 is rotated, there is a zone on each side of the swell of the barrel that allows the cream to gather, and thereby considerable energy is wasted.

It is shown from the foregoing that although my churn is of similar pattern and is operated similar to churning now in the market of this class, there are improvements in the details of the construction and the general arrangements which make my invention a 45 complete and efficient machine and give it superior advantage over others that are now in the market.

Having thus described my invention, what I claim, and desire to be protected in by Letters Patent, is—

1. A churn comprising a closable vessel of barrel form, said vessel being provided with concaved flutes or grooves arranged with their planes parallel to each other and parallel to the axis of the vessel; trunnions projected from the sides thereof; a supporting-frame for the vessel; two bearings vertically adjustable upon the said frame, and a vertically-adjustable detent adapted to engage with one of

the trunnions of the vessel and hold it in different positions as specified.

2. A churn comprising a closable vessel having flutes down each side forming convexed ridges on the inner opposite sides; and a closure for such vessel having an annular groove 70 therein to receive the open end of the vessel; diametrically-oppositely-arranged levers hinged at their outer ends to the fluted sides of the vessel, said levers having their adjacent or inner ends turned upward to form 75 hook members and near their outer ends bent to form fulcrums 29^a; a bar loosely fixed upon a stud projected up centrally from the closure, said bar having its ends engaging the adjacent ends of the levers and adapted when 80 pressed down to force the levers tightly against the closure, and means for pressing the said bar down, all being arranged substantially as shown and described.

3. In a churn of the class described having 85 the barrel form, parallel flutes on opposite sides thereof which form convex swells or ribs on the inner sides, trunnions fixed at the center of said flutes, conical ridges on said trunnions, bearings arranged in forks having 90 grooves for receiving the conical ridges, means for adjusting the bearings vertically, consisting of straps 20 embracing the bearings and the forks and set-screws taking through the straps and engaging one side of the forks all 95 substantially, as and for the purposes set forth.

4. In combination with a rigidly-braced frame having forked uprights and adjustable bearings arranged therein, a vessel having 100 fluted sides suitably mounted on trunnions which journal in said bearings, a vertical slideable holder 22 of elastic material having an angled opening at its upper end for receiving the angled end of one of the trunnions for 105 holding the churn at rest at any desired position.

5. In a churn of the character described, the combination with the churn-body; means for rotating it, and means for holding the said 110 churn in different positions; a cover for the open end and means for hermetically sealing the said cover upon the said ends; of a vent-nipple connected with the vessel near the end opposite the cover, said nipple having a removable cap provided with a vent; an elastic washer within the said cap, said cap, washer and vent in the said cap being so arranged that when the cap is screwed home the vent will be cut off from the nipple and when 120 screwed outward to remove the elastic packing from the nipple the vent is brought into communication with the nipple, all being arranged substantially as described.

BESSIE KINGSLEY.
